(57) **CLAIM**

The ornamental design for a reduced pressure treatment system, as shown and described.

DESCRIPTION

FIG. 1 illustrates a front perspective view of a reduced pressure treatment system having a fluid canister according to one embodiment of the invention;

FIG. 2 illustrates a front view of the reduced pressure treatment system;

FIG. 3 illustrates a right side view of the reduced pressure treatment system;

FIG. 4 illustrates a rear view of the reduced pressure treatment system;

FIG. 5 illustrates a top view of the reduced pressure treatment system; and,

FIG. 6 illustrates a bottom view of the reduced pressure treatment system.

The broken lines illustrated in the drawings are for illustrative purposes only and form no part of the claimed design.
